(57) **CLAIM**

The ornamental design for an electronic ballast, as shown and described.

DESCRIPTION

FIG. 1 is a right, front perspective view of an electronic ballast showing our new design;

FIG. 2 is a top plan view thereof;

FIG. 3 is a side elevation view thereof, the opposite side being a mirror image;

FIG. 4 is a front view thereof; and,

FIG. 5 is a rear view thereof.

The broken line showing of an electronic ballast represents unclaimed subject matter and forms no part of the claimed design.
